CERVICAL TRACTION UNIT

Frank J. Nightingale, 3169 Lincoln,
San Diego, Calif. 92104

Filed Mar. 4, 1968, Ser. No. 10,827

Term of patent 14 years

Int. Cl. D24—02

U.S. Cl. D83—1

Fig. 1

Fig. 2

Fig. 3

Fig. 4

FIGURE 1 is a perspective view of a cervical traction unit, showing my new design;

FIGURE 2 is a top plan view thereof;

FIGURE 3 is a side elevational view as taken from the opposite side to that shown in FIGURE 1; and

FIGURE 4 is an end elevational view as taken from the left hand end of FIGURE 3.

I claim:

The ornamental design for a cervical traction unit, as shown.
